The ornamental design for a set of educational building blocks to model nucleic acid structures, as shown and described.

DESCRIPTION

FIG. 1 is a perspective view of each building block in the set of educational building blocks according to the present invention, wherein the set includes a building block modeling a nucleotide with a base of adenine, a building block modeling a nucleotide with a base of guanine, a building block modeling a nucleotide with a base of thymine, and a building block modeling a nucleotide with a base of cytosine;

FIG. 2 shows the set of building blocks of FIG. 1, with each of the building blocks depicted in a left side view;

FIG. 3 shows the set of building blocks of FIG. 1, with each of the building blocks depicted in a right side view;

FIG. 4 shows the set of building blocks of FIG. 1, with each of the building blocks depicted in a bottom view;

FIG. 5 shows the set of building blocks of FIG. 1, with each of the building blocks depicted in a top view; and,

FIG. 6 shows a perspective view of the set of building blocks as assembled to model a DNA structure.

The broken lines represent portions of the article that form no part of the claim.
